UNITED STATES PATENT OFFICE

2,470,793

AEROCHEMICAL DEVICE

Frank Short, Haddam Neck, Conn.

Original application February 3, 1944, Serial No. 520,966. Divided and this application January 6, 1948, Serial No. 662

2 Claims. (Cl. 89—1.5)

(Granted under the act of March 3, 1883, as amended April 30, 1928; 370 O. G. 757)

1

The invention described herein may be manufactured and used by or for the Government, for governmental purposes, without the payment to me of any royalty thereon.

This invention relates to an efficient means for releasing and disseminating chemical warfare agents from aircraft in flight. The present application is a division of my parent application Serial No. 520,966, filed February 3, 1944, for Aerocchemical device which has now matured into Patent No. 2,442,381.

Up until now very few effective types of apparatus have been developed for discharging chemical warfare agents, such as toxic persistent liquids and incendiary substances, from airplanes. Chemical drop bombs, which explode and burst open only upon impact with the ground, have a limited tactical use because they have a low agent content efficiency and cannot be effectively used to cover targets of large area. To overcome deficiencies of drop bombs, spray tanks were developed since the last war. These tanks have a high chemical filling-to-weight ratio and good spreading capacity, but are bulky, complicated, difficult to prepare for action, subject to defective action, and somewhat costly.

An object of the present invention is to provide an apparatus which is simple in construction, safe to handle and release from an airplane, and with a high chemical efficiency and spreading action.

Another object is to provide an effective yet simple type of apparatus adapted for discharging a multitude of incendiary units and for laying down a shower of a persistent vesicant agent from the air, the apparatus being devoid of complications, such as fuses, explosive charges, electrical connections, intricate discharge lines and valves, or the like, for obtaining a discharge of the agent.

Further objects will become apparent from the following description and accompanying drawing.

For accomplishing the objects of this invention, a container is provided which may be of convenient size for attachment to standard bomb racks or, if desired, as large as standardized spray tanks. The container body or casing is constructed to have as an integral part a strip or band susceptible to being pulled or torn away by an adequate force, particularly a sudden torque force, imparted through a fastening means which remains secured to the plane when the container is released free of the plane in an orderly, controlled manner. When the strip or band is thus torn away, the container is opened

and makes a satisfactory discharge of the chemical agent without danger of contamination to the plane.

The container is preferably somewhat streamlined and stabilized so that it falls from the plane in a suitably controlled manner. It may be constructed of light material to have a high filling-to-weight ratio, but with adequate strength to withstand shipment and rough handling. Without intricate discharge lines and valves and without troublesome electrical connections or detonators, the container safely encloses the chemical agent filling and functions reliably to discharge the filling when desired. The invention will be described in more detail with reference to the drawing which illustrates an aerocchemical container for incendiary units embodying important features of the invention.

Figures 1 and 2 show a partly sectioned, longitudinal view and a cross-section view, respectively, of a typical incendiary agent container embodying principles of the invention.

Figures 3, 4, 5 and 6 illustrate how the container is held in an airplane by suspension lugs and show separate stages in the process of release and discharge.

Figures 7 and 8 show the construction of a recommended type of incendiary unit which forms part of the filling in the container.

Figures 9, 10 and 11 show how the incendiary unit functions upon hitting the ground.

Figure 12 shows a partly sectioned, longitudinal view of a typical container for a persistent vesicant agent.

Referring particularly to Figures 1 and 2, a plurality of incendiary units 1 is stored within the cylindrical casing or body 2, and the ends of the body somewhat streamlined or rounded in shape house spiral springs 3 and 4, tending to push the units together. In the body 2, and as an integral part thereof, is a central tear-strip 5 soldered into place and joining the two end parts of the body. The tear-strip 5 at a small loose end is provided with a loop 6, and a pull on this loop by an arming wire or cable 7 causes the container to rotate as it starts to fall and then imparts a sufficient sudden torque force at the end of the tear-strip to tear the strip from the body of the container with a jerk. The arming wire is of sufficient length to permit the container to fall a safe distance below the bomb-bay hatch before the tear-strip is twisted away from the container. When the tear-strip is thus removed, the container separates into two parts; and the springs 3 and 4 push out the incendiary

units 1, which then fall and scatter over a wide area.

As illustrated in Figures 3, 4, 5 and 6, the body of the container is provided with fixed suspension lugs 8 and 9 properly spaced so that the container can be attached to the releasing shackles 10 and 11 of a standard type bomb-rack bar. The arming wire 7 may be wrapped several times around the container body, as shown in Figure 2, and attached to a hook provided in notch 12 of the shackle bar. On release, as shown in Figure 5, shackles 10 and 11 are opened while the notch hook or shackle 12 remains closed. Thus the container begins to drop, and the arming wire causes the container to rotate a number of revolutions as it attains a certain rotative speed. When the arming wire 7 becomes extended its full length and attains full tension, the inertia of the revolving and falling container is sufficient to cause the tear-strip to become completely twisted off, as shown in Figure 6, without excessive shock or strain.

Further, as shown in Figure 6, with the container opened into two parts, the springs act to push out the incendiary units. The shackles 10 and 11 may be operated in the usual manner through mechanical or electrical means from within the cockpit or bombardier station of a plane. Likewise, the notch hook 12 may be operated to open and release the arming wire and attached tear-strip as a safety measure after the container has been released to the fullest extent.

At the tail end, the container is provided with a valve means 13 for removing air and forcing in an inert gas, such as nitrogen, and with an attached conical stabilizer or equivalent tail fin for keeping the container in a substantially steady position as it falls into the air stream.

As shown in Figures 7 and 8, the incendiary units may be made up of squares 15 and 16 about $\frac{1}{4}$ to $\frac{1}{2}$ inch thick. These squares may be made of Celotex or similar flammable fibrous material. They may be coated or impregnated with paraffin, or the like, to increase their combustibility and make them impermeable to air. The squares are joined together in pairs and preferably arranged as shown in Figure 8 to make a unit. A recess 17 may be provided in one or both of the squares as shown in Figure 7 on the side of the squares which becomes covered when the unit is put together. Within the recess is placed a phosphorus solution or suspension, and the unit is assembled as in Figure 8 by lightly melting paraffin or adhesive plastic with which the two squares are impregnated and sticking the squares together to set the adhesive. Thus, the phosphorus may be kept sealed in the unit indefinitely, particularly if the phosphorus solution is substantially encased in a plastic, adhesive material which prevents access of air, until the unit becomes separated.

After the double square units have been discharged from the container, they become distributed through the air and are kept from igniting by virtue of the sealed assembly described. Upon hitting the ground, in general, the individually frangible units tend to have an impact on one point or another, whereupon inertia forces them to separate as shown in Figure 10. When the unit becomes separated, the wet phosphorus suspension or solution becomes exposed to the air, and as the material becomes dried out by evaporation, the phosphorus becomes ignited and sets fire to the square. In this way extensive

fires can be started with a device of extremely simple construction.

The incendiary units may have various shapes. For example, they may be cubical, tubular, spherical, etc. However, they are preferably formed as receptacles which are frangible or subject to cleavage on sufficient impact corresponding to the impact they receive in hitting the target or ground after falling.

The flammable receptacles should be inert to their spontaneously ignitable contents and impermeable to air or should have an inner lining or container inert and impermeable in these respects for enveloping the spontaneously ignitable contents. The spontaneously ignitable material may include various substances, for example, unsaturated organic compounds which very rapidly and exothermically become oxidized in the presence of air and certain organo-metallic compounds. Solutions of these substances in flammable solvents may be placed within the receptacles provided they are in contact with materials to which they are inert. For example, a solution of divinyl acetylene or diethyl zinc in a hydrocarbon oil may be enveloped within a glass ampoule which, in turn, is enclosed by a receptacle made of a flammable material. In some instances the plastic used to envelop the spontaneously ignitable material may be one which is not readily flammable, as, for example, cellulose acetate. In having the spontaneously ignitable substance enveloped within a fibrous receptacle by glass or an inert plastic, the fibrous material of the receptacle may be chemically treated to increase its combustibility, as, for example, by nitration. In other instances the receptacles may be constructed of non-fibrous materials, such as nitro-cellulose plastic, or an ignitable metal, such as magnesium.

The frangible units may be safely protected against breaking and igniting in the container by proper packing, such as described, so that they remain unaffected until the individual units distributed from the opened containers fall and hit the target or ground.

Referring to Figure 12, the body of the container for a persistent liquid vesicant or similar toxic agent is shaped and constructed in much the same manner as the incendiary container illustrated in Figure 1. The liquid container does not necessarily require any internal projection means, such as springs, and may be filled to a proper level with a liquid agent, leaving a void for expansion. The container body may be made up with the tear-strip 5 in the midsection.

Methods other than soldering may be used for incorporating a tear-strip in the container. For example, the body may be fabricated as one piece but with a circumferential band 19 formed by partly shearing or stamping an indentation 20 onto the wall of the body. A loop 6 is firmly welded into the band for attachment to an arming wire or cable, and in at least one place a weakening indentation may be made across the band. The chemical container is also preferably provided with a threaded filling hole 21 for charging liquid into the container and closure plug 22 or equivalent valve means.

Like the incendiary container, the liquid container may be provided with a stabilizer 14 at the tail end to maintain the container in a horizontal position as it falls into the air stream below the bomb bay to avoid bumping and make the opening of the container with less shock. When

the chemical container is released and the force applied through the arming wire ruptures the container along the relatively weak indentations 20 defining the band 19, the container is opened and discharges the chemical content, which thereupon becomes broken up into a shower of liquid drops in the same fashion as a stream of liquid issuing from a spray tank.

The container and releasing assembly may be attached to a wing of an airplane. The container may be attached to a parachute.

The container casing may be made of sheet steel of about 10 to 20 gage. A tear-strip soldered to abutting sections of the casing may be somewhat thinner.

A number of variations may be made in the structure of the container with the tear-strip releasing means to suit tactical needs. For example, perforated plates may be fixed within the container to be near the outlets of the sections of the container so that the liquid is ejected at a slower rate when the tear-strip is torn away. Or, the container may be constructed to have a weighted nose which remains fixed to the stabilized tail end, so that the container falls like a bomb and ejects liquid through openings left where the tear-strip is removed. Such a device may be released from high altitudes and aimed at an area target to be contaminated. Provisions may be made in such a container to have air or gas pressure or spring-activated piston means aid in forcing the liquid out as the container increases in velocity and descends toward the target. Also, an impact-detonated explosive charge may be incorporated into the container, as, for example, in the weighted nose to give added anti-personnel effects and aid in checking the place where the container hit the ground.

Thus, it is to be understood that various modifications come within the spirit and scope of the invention.

I claim:

1. A liquid tight container adapted for releasing and disseminating a persistent vesicant liquid in the air stream of an air craft in flight, 45 comprising a thin elongated sheet metal casing having an integral thin metal midsection provided with indented marginal portions and being susceptible to being ruptured and torn away

from the container by a sudden torque force, adjacent integral tubular portions having substantially semi-spherical end portions, means for charging the casing with the liquid, a fastening on said midsection for attaching an arming cable through which the torque force is applied, and a suspension lug fixed to each of said tubular portions for attachment to a releasing shackle on said air craft.

2. A liquid tight container adapted for releasing and disseminating a persistent vesicant liquid in the air stream of an air craft in flight, comprising a thin elongated sheet metal casing having an integral thin metal midsection provided with indented marginal portions and being susceptible of being ruptured and torn away from the container by a sudden torque force, adjacent integral tubular portions having substantially semi-spherical end portions, means for charging the casing with the liquid, a fastening on said midsection for attaching an arming cable through which the torque force is applied, a suspension lug fixed to each of said tubular portions for attachment to a releasing shackle on said aircraft, and a stabilizing fin attached exteriorly to one on said end portions for holding the longitudinal axis of said container approximately in alignment with the direction of the air stream of said air craft.

FRANK SHORT.
